DESIGN FOR GOOGLES

Frank W. Maurer, Newton Highlands, Mass.

Application December 29, 1943, Serial No. 112,113

Term of patent 14 years

(Cl. D57—1)

To all whom it may concern:

Be it known that I, Frank W. Maurer, a citizen of the United States, residing at 301 Lake Avenue, Newton Highlands, in the county of Middlesex and State of Massachusetts, have invented a new, original, and ornamental Design for Goggles, of which the following is a specification, reference being had to the accompanying drawing, forming part thereof.

The essential features of my design reside in the parts shown in full lines, and the head band is shown fragmentarily in Fig. 2 for convenience of illustration.

I claim:

The ornamental design for goggles, substantially as shown and described.

FRANK W. MAURER.
